UNITED STATES PATENT OFFICE.

JOHN MITCHELL, OF ROCHESTER, NEW YORK, ASSIGNOR TO CLARK'S COKING AND SMOKELESS FURNACE COMPANY, OF SAME PLACE.

FURNACE.

SPECIFICATION forming part of Letters Patent No. 461,444, dated October 20, 1891.

Application filed December 24, 1890. Serial No. 375,715. (No model.)

To all whom it may concern:

Be it known that I, JOHN MITCHELL, a citizen of the United States, residing at Rochester, New York, have invented certain improvements in Furnaces, of which the following is a specification, reference being had to the accompanying drawings.

My invention relates to certain improvements in furnaces for steam-boilers, whereby the production of smoke is prevented and increased efficiency is secured along with durability and cheapness of construction.

My improvements are fully described and illustrated in the following specification and the accompanying drawings, and the novel features thereof specified in the claims annexed to the said specification.

In the accompanying drawings, representing a steam-boiler furnace embodying my improvements, Figure 1 is an elevation, the front of the furnace being removed. Fig. 2 is a transverse section on the line 2 2, Fig. 3. Fig. 3 is a plan. Fig. 4 is a central longitudinal section.

In the accompanying drawings, representing my improved furnace as applied to a steam-boiler, A is the boiler; B, the front grate, on which the coal is partially burned or coked; C, the rear grate, on which the combustion is completed; D, the bridge-wall, and E E', the descending-flues, through which the volatile or gaseous products of the combustion on the front gate are conveyed underneath the rear grate, so as to secure their complete combustion by passing upward through the incandescent material thereon. The grates are placed on the same horizontal level, or so that the combustible can be transferred from the front to the rear grate, and an opening F is formed in the bridge-wall immediately above the grates through which the coked or partially-burned coal is transferred from the front to the rear grate. In practical use the coal is kept piled up on the front

grate, so as to close or partially close the opening F, thereby compelling the gases and volatile matters to pass into the flues E E' through openings G G' in the bridge-wall. Provision is made for admitting air underneath the rear or secondary grate through a suitable draft-opening provided with a

damper. The boiler is of any ordinary type provided with the return-flues H.

The side walls I I of the boiler-setting are constructed in any ordinary way of dimensions suitable to the size of the boiler, and the rear wall J is placed at such a distance from the rear end of the boiler as to permit the products of combustion to pass upward and enter the flues H.

K is the front of the boiler, provided with the usual doors, and L the uptake.

The bridge-wall is provided below the grates with a door M, through which the ashes are removed from underneath the secondary grate. The opening F in the bridge-wall above the grate is preferably made in the form of an arch, constructed of any suitable fire-brick N, which are set in two rows with broken joints, as indicated by the full and dotted lines in Fig. 1, so that in case one or more of the bricks in one row should be broken or crack off the arch will still be preserved by the bricks of the other row, so that there is no gap or opening through which air

or gases can obtain access directly to the combustion-space above the secondary grate without passing through the flues E E'. Above the arch the bridge-wall is continued all the way up to the lower side of the boiler

or other surface which it is designed to heat, except that the openings G G' are formed in the wall, through which the gaseous products of the primary combustion obtain access from above the front grate to the descending flues E E', which open into the space underneath the secondary grate.

Air is admitted under the secondary grate through a suitable passage provided with a regulating valve or damper. This passage for a single boiler is arranged at one side, as indicated at O, Fig.

2, or for a battery of boilers may be placed in the bridge-wall below the grates, as shown at O', Fig. 1, or may enter from the rear, as at O'', Fig. 3.

The flues E E' are built of brick or in any other suitable way, being closed on all sides, except as they are provided with the openings G G', and are open at their lower ends into the space below the secondary grate. At the inner sides the flues are formed by the walls P P', which separate the flues from

the combustion-chamber above the secondary grate. The rear walls of the flues Q Q' extend upward to the boiler.

At its rear side the secondary combustion-chamber communicates with the passage R underneath the boiler and through which the flame and hot gases pass to the flues H.

It will be observed that under certain circumstances or for small furnaces one of the descending flues may be dispensed with, the remaining one being made of sufficient dimensions to conduct away the gaseous products from the primary fire. It will also be obvious that other changes may be made in the construction and arrangement—such, for instance, as inclining the descending flue or locating it outside the side wall or at the side of the front grate—without departure from the principle involved therein. My improved furnace may also be applied to purposes other than heating boilers.

In the operation of my improved furnace, the coal, which has been coked or partially burned on the primary grate, is pushed backward from time to time onto the secondary grate through the opening in the bridge-wall, so as to keep the rear grate uniformly covered with a layer of incandescent combustible. Under these circumstances the combustion on the secondary grate is perfect and the smoke or gas from the partial combustion on the primary grate is entirely consumed in passing through the fire on the secondary grate, as I have demonstrated by practical use extending over a considerable period of time.

In practice I have found the following proportions satisfactory for a boiler four feet in diameter: front grate, forty inches by forty inches; secondary grate, twenty-one inches by thirty inches, and flues nine inches by twenty-one inches.

Coking-chambers, arranged at the side of a grate and of the combustion-chamber and provided with a conduit for gases, extending across the front of and above said grate, were known prior to my invention. In such construction the coke could be poked out onto the grate. The inner wall of the coking-chamber was liable to be speedily burned out. By my construction the coking-chamber is placed in front and the grate C directly behind it, the interposed bridge-wall being pro-

vided with suitable opening, being so related to the two grates that the coke can be pushed through the front door directly back onto the rear grate; and, further, the gases from the coking coal are, together with air for combustion, delivered directly under the rear grate and at both sides thereof, thus more thoroughly distributing them and avoiding also the obstruction of the front of the grate by the conduit above referred to.

I claim—

1. The combination, in a furnace, of the primary grate B and secondary grate C, arranged one in front of the other to permit the transfer of the combustible from the primary to the secondary grate, and separated from each other by the wall D, having opening F immediately above the grates, one or more descending flues E, constituting a communicating passage between the chamber above the primary grate and the space below the secondary grate, and a suitable air-inlet passage through which air is supplied to the combustion on the secondary grate, substantially as described.

2. The combination, in a furnace, of the primary and secondary grates B and C, the intermediate bridge-wall D, having immediately above the grates the opening F, provided along its upper edge with the double row of fire-brick N, arranged with broken joints, and a passage or flue communicating between the chamber over the primary grate and the space underneath the secondary grate, substantially as described.

3. The combination, in a furnace, of the primary grate B and secondary grate C, arranged one in front of the other to permit the transfer of the combustible from the primary to the secondary grate, and separated from each other by the wall D, having opening F immediately above the grates, and the openings G G' in the upper part of the wall, the descending flues E E', arranged on opposite sides of the secondary grate, and a suitable air-inlet passage through which air is supplied to the secondary grate, substantially as described.

JOHN MITCHELL.
